UNITED STATES PATENT OFFICE.

HENRY B. KNIGHT, OF BATTLE CREEK, AND GEORGE M. COGSWELL, OF DOWAGIAC, MICHIGAN.

FIFTH-WHEEL.

No. 855,954.

Specification of Letters Patent.

Patented June 4, 1907.

Application filed January 16, 1907. Serial No. 352,663.

To all whom it may concern:

Be it known that we, HENRY B. KNIGHT and GEORGE M. COGSWELL, citizens of the United States, residing at the city of Battle Creek, county of Calhoun, State of Michigan, and the city of Dowagiac, county of Cass, and State of Michigan, respectively, have invented certain new and useful Improvements in Fifth-Wheels, of which the following is a specification.

This invention relates to improvements in fifth wheels.

The main object of this invention is to provide an improved roller bearing short turn fifth wheel which is very strong and durable and at the same time comparatively economical to produce and one which is adapted for use in connection with elliptical springs for the support of a vehicle body.

Further objects, and objects relating to structural details will definitely appear from the detailed description to follow.

We accomplish the objects of our invention by the devices and means described in the following specification.

The invention is clearly defined and pointed out in the claims.

A structure embodying the features of our invention is clearly illustrated in the accompanying drawing, forming a part of this specification, in which:

Figure 1 is a detail plan of our improved fifth wheel. Fig. 2 is a detail transverse section taken on a line corresponding to line 2—2 of Fig. 1 through the bearing segments showing the form and arrangement thereof and of the arrangement of the rollers. Fig. 3 is a detail front elevation of our improved fifth wheel, a portion of the upper bearing segment 4 being broken away to show structural details. Fig. 4 is a longitudinal central section thereof taken on a line corresponding to line 4—4 of Fig. 3. Fig. 5 is a detail section taken on a line corresponding to line 5—5 of Fig. 4. Fig. 6 is an inverted detail of the upper bearing segments 4. Fig. 7 is a detail plan view of the lower bearing segment 5.

In the drawings the sectional views are taken looking in the direction of the little arrows at the ends of section lines, and similar reference characters refer to similar parts throughout the several views.

Referring to the drawing, 1 represents the

axle of a vehicle, 2 the head block, and 3 an elliptical spring.

The upper member of our improved fifth wheel consists of the bearing segment 4, which is channel-shaped in cross section opening downwardly. A cross-piece 12 is provided, forming a seat for the head block 2. The cross-piece is provided with laterally projecting perforated ears 14. The clips 13 by means of which the head block 2 and spring 3 are secured are arranged through these perforated ears 14. To further aid in securing the head block upturned flange-like lips 23 are provided for the cross-piece. Projecting rearwardly from this cross-piece 12 are diverging arms 15 upon which the forward ends of the reaches 6 are secured. On the inner sides of these arms at their forward ends are upturned flange-like lips 16 which assist in retaining the reaches thereon. At the rear ends of the arms 15 is a cross-piece 17 having a king bolt bearing thereon. Extending from the rear ends of the upper bearing segment to the arms 15 are brace arms 18. This makes a very strong and at the same time light construction and enables the easy securing of the parts rigidly thereto.

The lower bearing segment 5 is adapted when the parts are assembled to project into the upper bearing segment as clearly appears in Fig. 3. The lower bearing segment is provided with a cross-piece 19 adapted to rest on the top of the axle to which it is secured by suitable clips 20. The arms 21 project rearwardly from the bearing segment and are provided at their rear ends with a king bolt bearing. To further support the king bolt 8 and to brace the parts braces 7 extending from the axle to the king bolt are provided, the rear ends of the braces being provided with a suitable king bolt bearing. The clips 20 secure the braces 7 to the axle.

A pair of bearing rollers 10 provided with suitable journals are arranged in the upper bearing segment, being preferably located slightly in advance of the head block. These bearing rollers travel upon the lower bearing segment 5, which is provided with a flat face, the bearing portion thereof having a slot 11 therein. See Fig. 7. This allows any dirt which may get into the bearings to escape. However, owing to the shape and arrangement of the bearing members, the bear-

ing portions are very effectively protected from the dirt.

To effectively secure the parts of the bearing segments together the segment 4 is provided with a central downwardly projecting lug or boss 22, which projects through the slot 11 in the lower bearing segment. A bolt 9 is arranged through this lug or boss, on the lower end of which is a nut which serves to retain the parts at this point. See Figs. 4, 5 and 6.

By arranging the parts as we have illustrated and described we secure a very rigid and strong construction, although the same 15 may be made of comparatively light material. The bearing portions also very readily free themselves from dirt. The structure is especially adapted and designed by us for use with the double elastic springs, although it 20 may be adapted for use in connection with other springs.

We have illustrated and described our improved fifth wheel in detail in the form preferred by us on account of structural simplicity and economy and the strength and rigidity of the parts when so arranged. We are, however, aware that it is capable of considerable variation in structural details without departing from our invention.

30 Having thus described our invention, what we claim as new and desire to secure by Letters Patent, is:

1. In a structure of the class described, the combination with an axle, of a head block; a spring arranged thereon; rearwardly-diverging reaches; an upper member, consisting of a bearing segment channel-shaped in cross-section, opening downwardly, having a central downwardly-projecting lug thereon, a cross-piece adapted to receive said head block having upwardly-projecting flange-like lips adapted to engage the same and having perforated ears thereon, a pair of rearwardly-diverging arms on which said reaches are arranged and secured, said arms having upwardly-projecting flange-like lips at their inner ends to assist in retaining said reaches, brace arms extending from the ends of said bearing segment to said arms, a cross piece connecting said arms at their rear ends having a king bolt bearing thereon; clips arranged over said springs and head block and through the perforated ears on said cross piece securing the parts together; a lower member, comprising a bearing segment arranged to project into the said upper bearing segment having a longitudinal slot therein adapted to receive the said downwardly-projecting lug on said upper bearing segment, a cross piece for said lower member adapted to rest on the axle, rearwardly projecting converging arms having a king bolt bearing at their rear ends; a brace extended to the under side of the axle, said brace having a king bolt bearing thereon; clips for securing the

parts together and to the axle arranged over the said cross piece of said lower member and through said brace; a king bolt; bearing rollers journaled on said upper bearing segment in front of said head block; and a bolt 70 arranged through the said central lug of said upper bearing segment adapted to retain said lower bearing segment thereon, for the purpose specified.

2. In a structure of the class described, the combination with an axle, of a head block; a spring arranged thereon; rearwardly-diverging reaches; an upper member, consisting of a bearing segment channel-shaped in cross-section, opening downwardly, having a central downwardly-projecting lug thereon, a cross-piece adapted to receive said head block and having perforated ears thereon, a pair of rearwardly-diverging arms on which said reaches are arranged and secured, brace arms extending from the ends of said bearing segment to said arms, a cross piece connecting said arms at their rear ends having a king bolt bearing thereon; clips arranged over said springs and head block and through the perforated ears on said cross piece securing the parts together; a lower member, comprising a bearing segment arranged to project into the said upper bearing segment having a longitudinal slot therein adapted to receive the said downwardly-projecting lug on said upper bearing segment; a cross piece for said lower member adapted to rest on the axle, rearwardly projecting converging arms having a king bolt bearing at their rear ends; a brace extended to the under side of the axle, said brace having a king bolt bearing thereon; clips for securing the parts together and to the axle arranged over the said cross piece of said lower member and through said brace; a king bolt; bearing rollers journaled on said upper bearing segment in front of said head block; and a bolt arranged through the said central lug of said upper bearing segment adapted to retain said lower bearing segment thereon, for the purpose specified. 110

3. In a structure of the class described, the combination with an axle, of a head block; a spring arranged thereon; rearwardly-diverging reaches; an upper member, consisting of a bearing segment channel-shaped in cross-section, opening downwardly, having a central downwardly-projecting lug thereon, a cross-piece adapted to receive said head block and having perforated ears thereon, a pair of rearwardly-diverging arms on which said reaches are arranged and secured, a cross piece connecting said arms at their rear ends having a king bolt bearing thereon; clips arranged over said springs and head block and through the perforated ears on said cross piece securing the parts together; a lower member, comprising a bearing segment arranged to project into the said upper bearing segment having a 130

longitudinal slot therein adapted to receive the said downwardly-projecting lug on said upper bearing segment, a cross piece for said lower member adapted to rest on the axle, 5 rearwardly projecting converging arms having a king bolt bearing at their rear ends; a brace extending to the under side of the axle, said brace having a king bolt bearing thereon; clips for securing the parts together 10 and to the axle arranged over the said cross piece of said lower member and through said brace; a king bolt; bearing rollers journaled on said upper bearing segment in front of said head block; and a bolt arranged through 15 the said central lug of said upper bearing segment adapted to retain said lower bearing segment thereon, for the purpose specified.

4. In a structure of the class described, the combination with an axle, of a head block; a spring arranged thereon; rearwardly-diverging reaches; an upper member, consisting of a bearing segment channel-shaped in cross-section, opening downwardly, a cross-piece adapted to receive said head block and having perforated ears thereon, a pair of rearwardly diverging arms on which said reaches are arranged and secured, a cross piece connecting said arms at their rear ends having a king bolt bearing thereon; clips 25 arranged over said springs and head block and through the perforated ears on said cross piece securing the parts together; a lower member, comprising a bearing segment arranged to project into the said upper bearing 30 segment, a cross piece for said lower member adapted to rest on the axle, rearwardly projecting converging arms having a king bolt bearing at their rear ends; a brace extended to the under side of the axle, said brace having a king bolt bearing thereon; clips for securing the parts together and to the axle arranged over the said cross piece of said lower member and through said brace; a king bolt; and bearing rollers journaled on 45 said upper bearing segment, for the purpose specified.

5. In a structure of the class described, the combination with an axle, of a head block; a spring arranged thereon; a reach; 50 an upper fifth wheel member, consisting of a bearing segment channel-shaped in cross-

section, opening downwardly, having a central downwardly-projecting lug thereon, and having a rearwardly projecting arm having a king bolt bearing thereon, secured to said 55 reach and head block; a lower member, comprising a bearing segment arranged to project into the said upper bearing segment having a longitudinal slot therein adapted to receive the said downwardly-projecting lug 60 on said upper bearing segment, and a rearwardly projecting arm having a king bolt bearing secured to the axle; a brace, having a king bolt bearing thereon extending to the under side of the axle; a king bolt; bearing 65 rollers journaled on said upper bearing segment in front of said head block, and a bolt arranged through the said central lug of said upper bearing segment adapted to retain said lower bearing segment thereon, for the 70 purpose specified.

6. In a structure of the class described, the combination with an axle, of a head block; a spring arranged thereon; a reach; an upper fifth wheel member, consisting of 75 a bearing segment channel-shaped in cross-section, opening downwardly, having a central downwardly-projecting lug thereon, and having a rearwardly projecting arm having a king bolt bearing thereon, secured to said 80 reach and head block; a lower member, comprising a bearing segment arranged to project into the said upper bearing segment having a longitudinal slot therein adapted to receive the said downwardly-projecting lug 85 on said upper bearing segment, and a rearwardly projecting arm secured to the axle, said arm having a king bolt bearing thereon; bearing rollers journaled on said upper bearing segment in front of said head block, and 90 a bolt arranged through the said central lug of said upper bearing segment adapted to retain said lower bearing segment thereon, for the purpose specified.

In witness whereof, we have hereunto set 95 our hands and seals in the presence of two witnesses.
